UNITED STATES PATENT OFFICE.

BENTON C. ROWELL, OF CHICAGO, ILLINOIS; LILLA C. ROWELL EXECUTRIX OF BENTON C. ROWELL, DECEASED.

MECHANISM FOR OPERATING RAILWAY BLOCK-SIGNALS.

1,189,177.

Specification of Letters Patent. Patented June 27, 1916.

Application filed July 14, 1910. Serial No. 571,889.

To all whom it may concern:

Be it known that I, BENTON C. ROWELL, a citizen of the United States, residing in Chicago, in the county of Cook and State 5 of Illinois, have invented a new and useful Improvement in Mechanism for Operating Railway Block-Signals, of which the following is a specification.

This invention relates to block signaling 10 systems and especially to the mechanism employed for automatically operating the signals so that when a train enters a block, it not only clears that block for its own passage but also blocks all other trains from 15 entering the same block while it remains thereon.

The invention has been devised especially for use on a single track railway over which the trains move in both directions, and upon 20 those tracks embraced in double track systems upon which the direction of the trains is reversed at times, and its construction and operation are fully set forth in the description given below, and will be fully understood when considered in connection with 25 the accompanying drawing, in which—

Figure 1 is a plan of a section of railroad track equipped with my present invention, Fig. 2 is a plan view of the power 30 storage machine of the mechanism and the adjacent parts; Fig. 3 is a side elevation of the same. Fig. 4 is a side elevation showing the side opposite to that shown in Fig. 3. Fig. 5 is an end elevation. Fig. 6 is an 35 elevation of the end opposite to that given in Fig. 5. Fig. 7 is a horizontal section, the power storage cylinder being omitted. Figs. 8 and 9 each show portions of a partial transverse vertical section on line 8—8 40 of Fig. 3. Figs. 10, 11, 12, 13, and 14 are sections on the lines 10—10, 11—11, 12—12, 13—13, and 14—14 respectively of Fig. 7. Fig. 15 is a section on the line 15—15 of Fig. 13. Fig. 16 is a section on the line 45 16—16 of Fig. 8, Fig. 17 is a section on the line 17—17 of Fig. 2. Fig. 18 is a section on the line 18—18 of Fig. 13. Figs. 19 and 20 are sections on the lines 19—19 and 20—20 respectively of Fig. 3. Fig. 21 is a 50 section on the line 21—21 of Fig. 17. Figs. 22 and 23 are sections on the lines 22—22 and 23—23 respectively of Fig. 2. Figs. 24 and 25 are sections on the lines 24—24 and 25—25 respectively of Fig. 23. Figs. 55 26 and 27 are detail plans of the selecting

mechanism. Fig. 28 is an end view of the electric devices controlling the release of power from the power storing cylinder. Fig. 29 is a side elevation of the same. Fig. 30 is a detail of the prevention plate used 60 in said electric devices. Fig. 31 is a detail of the devices for locking the armature of said electric devices. Fig. 32 is an end view of the magnets for controlling the selector. Fig. 33 is a side view of the same, 65 Fig. 34 being a section on the line 34—34 of Fig. 32. Fig. 35 shows the electric wiring connecting the magnets to the track. Fig. 36 is a detail of one of the reversing relays. Fig. 37 is a sectional view of the 70 gear 81 and adjacent parts. Fig. 38 is a view similar to Fig. 36 showing the arrangement of the relay 250 when the points 3, 3 are in closed condition; Fig. 39 is an enlarged diagrammatic view of the wiring on 75 the slide 290 and attendant parts

The central feature of my improved signal setting mechanism is the spring power storing cylinder 10 mounted upon the shaft 41 supported in bearings 42 and 43 at its 80 ends. Inside of the cylinder are a series of flat metal springs 44 coiled about the shaft, and having their opposite ends secured to the shaft and to the cylinder as shown in Fig. 21, so that they may be tightened by 85 rotating the cylinder. This is done by the passing trains whether moving to the right or to the left through the medium of a lever 45 pivoted at 46 and having one end extended close up under the tread of the 90 track rail 47, and provided with a bearing block 48 the upper surface of which is slightly above that of the tread of the rail so that each wheel of any train moving over said rail depresses the end of lever 45, carrying said block 48 downward and raising the farther end of the lever correspondingly. (See Figs. 8 and 9). The motion at the farther end is much greater than that at the track, and to this farther end is attached a vertical rack 49 having a guide 50 the converging points 51 of which are entered in grooves formed upon opposite sides of the rack. The guide is supported stationarily by the longitudinal frame channel beam 53. The rack meshes with a gear 54 mounted upon the hub of the cylinder, and when the rack is actuated by the lever 45, it gives motion to the cylinder, through the pawls and ratchet hereinafter described, in 100 105 110

the proper direction to wind up the springs 44. The gear is free to turn back, to allow the rack and lever to return to normal position after each impulse received as stated 5 from the passing train. The construction by which the gear 54 is thus made to wind up the springs and to turn back idly without turning the shaft 41 is best shown at Figs. 17 and 19. At the side of the gear 10 is a ring 55 moving with the gear, and surrounding a circular ratchet 56 fast upon the hub of the cylinder 40, and in the ring are located a series, preferably four in number, of pawls 57 each adapted to engage with 15 the ratchet, and each provided with a depressing spring plunger 58. These pawls are adapted to carry the ratchet with them when the ring is moved by power received by the rack from the train and thereby to 20 rotate the cylinder and wind up the power springs, and the pawls ride idly over the ratchet when the latter turns back after each operation to allow the rack and lever to resume their normal positions. I also 25 place under the lower part of the ratchet, a series of check pawls 59 mounted upon a stationary cross brace 60 supported by the longitudinal beams 53 and 61. These check pawls are located at one side of the plane 30 of the actuating pawls, 57, so that they do not interfere therewith, and the ratchet is provided with a wide face to permit this location. The pawls 59 are intended to prevent any backward motion of the ratchet 35 56 and the cylinder 40. The power thus stored in the springs 44 is expended in operating the danger and clear signals of the block as hereinafter set forth. The cylinder 40 is adapted to receive a plurality of power 40 springs, and I adapt it to hold a large number of them so that without changing the construction of the cylinder, it can be used both where a full number is required and where a less number will furnish the 45 amount of power needed.

The signal boards 62 and 63 one for each direction are operated by power from said springs 44. The members referenced 300 and 301 designate what are variously 50 termed track instruments, train stops or safety stops and are also operated by springs 44 and they are always in opposing positions, one being at "danger" whenever the other is at "clear." They frequently 55 change position so that the "clear" instrument will be at "danger" and the "danger" instrument will be at "clear," but such changes are simultaneous and in no case do they lose their position relative to each 60 other, but are always opposed.

A very considerable amount of power is accumulated and constantly retained in the springs 44, and for the proper control of this power so that limited amounts of it 65 can be used from time to time as required

for the positioning of the signal boards, and track instruments I employ controlling mechanism embodying magnets, and the mechanism is also adapted to reduce the shock of the motor so that a slight amount 70 of power only in comparison with the amount stored in the springs 44 will be received at the magnets. This mechanism by which the power of the springs is controlled is desirably constructed as follows: Upon 75 the shaft 41, already mentioned I mount two large disks, 64 and 65 which I call locking disks, and these are each provided upon their peripheries at diametrically opposite points with abrupt shoulders or stops 66, 80 66. In proximity to the peripheries of the disks are two sliding lock bolts 67, 67 one adapted to engage the shoulders upon one of the disks and the other to engage those upon the other disk. The disks are rigid 85 upon the shaft 41 and are relatively keyed thereto so that the shoulders upon one are located midway circumferentially of those upon the other, thereby adapting them to arrest the shaft at each quarter turn. The 90 bolts are located at the same level in a housing 68, and they act alternately in arresting the disks at the end of one fourth of a revolution each time they release the disks and allow the power springs to operate. The bolts are pierced as seen at Fig. 20, and a double eccentric 69 upon a shaft 70 passing through them slides them into operative position relative to the disks in alternate order, and also retracts them alternately so that only one of the bolts acts at 95 a time.

The shaft 70 is operated as follows: On it is a gear 71 loosely mounted, Fig. 5, and a coiled spring 72 is joined at one end to 100 the shaft and at the other end to the gear as shown at Fig. 22, and this gear meshes with another gear 73 twice its size, on shaft 41. The gear 73 moves with shaft 41 a quarter turn at each operation, and consequently 105 shaft 70 is given a half turn at each operation. These movements of gear 71 tighten the spring 72, which possesses sufficient power when tightened to rotate shaft 70 and thereby to withdraw the bolts from under the shoulders of the locking disks, when the shaft 70 is released as now to be stated. Shaft 70 is controlled by a disk 74 having 110 diametrically opposite stops 75 on its periphery and these stops are arranged in different planes so that they are adapted to be engaged alternately by the swinging arms 76, 76, pivoted at 77, and each having extensions 78, 78 having forked ends straddling eccentrics 79, 79, on shaft 80. The 115 rotation of shaft 80 is adapted to cause the swinging of arms 76 and to withdraw the one which at the time is under one of the stops 75, thus permitting shaft 70 to turn under the power of spring 72 through a 120 125 130

half revolution, or until the other arm 76 engages the other stop 75.

The shaft 80 carries a gear 81 loosely mounted thereon, meshing with the gear 73 already mentioned on the main shaft. In the gear 81, see Fig. 37, is a spring similar to spring 72 coiled about the shaft with one end made fast thereto and the other end made fast to the gear, and this spring is adapted to turn the shaft whenever the controlling disk 83 rigidly mounted on the shaft is released as now to be described. The disk carries two sets of stops, those marked 84 being on the periphery, see Fig. 3 and those marked 85 on the side face, see Fig. 5 the latter stops being at different distances from the axis. The stops 84 encounter a sliding plate 86, and arrest the disk and deprive it of its momentum just previous to the contact by the stops 85 with the armature 87 of the magnet 88 which is energized by the approaching train in a manner hereinafter described, to set the signal to clear. The plate is moved immediately from its position after arresting the disk to one which presents the depression 89, see Fig. 7 to the stop 84, allowing the stop to move past the plate so that the disk can turn the short distance necessary to bring one of the stops 85 into engagement with the armature 87. The extent of this last movement of the disk is so very limited that it gains only slight momentum in the latter, and consequently the ensuing engagement with the armature is of a nature which gives no shock whatever to the armature or magnet, and has no tendency to disturb the electrical connections. The deenergizing of magnet 88 caused by the train as it passes the signal, results in the spring which acts on the armature 87 and the foot 227 acting as a weight moving the armature out from its engagement with the stop 85 and leaves the disk 83 free to move through a half revolution under the power of the spring in gear 81 and until the other stop 84 rests against the plate 86 and arrests the disk long enough to deprive it of its momentum. The plate 86 now again moves out of the way of stop 84 and allows the parts to turn and bring the other stop 85 into engagement with the armature thus completing a half revolution of the disk 83. This last movement of shaft 80 releases the train of mechanism described and allows the main motor to operate the signals to the danger position which it does through mechanism to be described later on. This engagement between the stop and the armature continues until another train approaches and the magnet 88 is again energized when the operation described is repeated. The means whereby the plate 86 is reciprocated will be set forth in a later part of this description.

For the purpose of preventing any excessive winding of the motor cylinder I have adopted the means following: The gear 73 above mentioned in addition to the duties already described as devolving upon it, meshes with and drives a gear 90, see Figs. 2 and 4, upon a short shaft 91 arranged parallel with shaft 41 and supported at one end by a bearing 92. A portion of the length of shaft 91 is screw threaded, and such threaded portion is entered in and engages the enlarged and interiorly threaded portion 93 of the sleeve 94, having a bearing 95. The sleeve is feathered to gear 96 so that it turns said gear, and gear 96 is in mesh with gear 97 fast upon the hub of the motor cylinder. It results from this construction that when the motor cylinder is actuated by a passing train, it acts through the gears 96 and 97 to turn sleeve 94, and as the sleeve turns, it will, by its threaded engagement, be drawn over and on to shaft 91. The sleeve is provided with a collar 98, and when the sleeve is slid as just stated, the collar encounters a swinging latch 99, pivoted at 100 and compresses the spring 101 on the rod 102 without moving the rod, which passes freely through an opening in the lower end of the latch. In this manner power is stored in spring 101 which when the rod is released, will move the rod 102 longitudinally and through its connection to the arm 103 on pivot 104 rigidly joined to the pawl 105, cause said pawl to quickly engage the rack teeth 106 on the side face of the winding up rack 49 and thereby hold up the rack and retain it in its raised position. In so doing the rack holds the outer end of lever 45 up and consequently the end carrying the tread 48 is held down so that the car wheels will pass idly over said tread without imparting any actuations to the lever. The engagement by the pawl 105 with rack 106 should be quick and for the full depth of the rack teeth in order to avoid injury to the teeth, and to insure this I provide a dog 107 stationarily located at 108 and adapted to engage a shoulder 109 on the underside of rod 102 and hold the rod against the power of spring 101 until the dog is drawn out of action. This is done by the wire 110 attached at one end to the bottom of latch 99, and having its other end passed through the depending leg of dog 107 and bent at right angles in front of said leg as seen at Fig. 4. When the sleeve moves forward as presently to be explained the wire 110 will draw the leg 107 of the dog and cause the dog to release the rod 102, so that the latter can then yield to spring 101 and carry the pawl 105 into full and instant engagement with the rack 106. While the winding up actuations of the motor cylinder cause the sleeve to move over and on to the shaft 91 as described, the turning of the

shaft 41 of the motor in operating the signals, results in the actuation of shaft 91 and this movement is in such direction as causes the sleeve to travel back and off from shaft 5 91. The engagement between pawl 105 and the teeth 106 of rack 49, lasts during such time as the motor cylinder remains wound up to its full capacity, but ends whenever the shaft 91 is unwound sufficiently to bring 10 about contact by the collar 98 with an arm 111 on the latch 99 and actuate the latter in the reverse direction from that received while the motor was being wound up. In 15 this reverse movement the latch encounters the pin 112 inserted in rod 102 and carries the rod back to its starting position so that the pawl 105 is freed from the rack teeth 106 and the rack is left free to resume the winding up of the motor. At the same time the 20 dog 107 is returned to its position in engagement with shoulder 109 by any suitable means such as a spring 107^a. The rack carrying the teeth 106 falls to its normal position by gravity, and this causes the lever 45 25 to resume its normal position and elevate the tread 48 so it will be operated by the next passing train.

The mechanism as so far described is adapted to be used with either single track 30 railways on which the trains move both ways, or with double track railways on which all the trains upon the same track move in the same direction. To adapt the apparatus to use upon the single track rail- 35 way it is necessary to combine with the power mechanism for operating the signals suitable selecting means, so that each train may control the setting of signals and cause them to be set in accordance with the direc- 40 tions in which the train is traveling, and the selecting means must do this whether the train is moving from east to west for instance, or from west to east. For this purpose, I provide two magnets 120 and 121, 45 see Figs. 32 and 33 having a single armature 122 between them and serving both. Both magnets are connected by wires to the track, and when the first train approaches from the east, for instance, the magnet 120 50 is energized, and when the first train approaches from the other direction the magnet 121 is energized. Each magnet draws the armature toward itself, so that the latter reverses if at the time any train passes 55 it does not happen to be in contact with the magnet properly energized by that train, and by so doing causes the operation of the signals in accordance with the direction of the train and the reversal of the track in- 60 struments if they do not at the time occupy the proper positions, as will be understood from what follows. The armature is pivoted at 123, and swings from one magnet to the other and has two positions only, and 65 is always in contact with one or the other

magnet. It has upon one side a projecting finger or lug 124 and through this finger it acts as a stop to the wheel 125 upon a shaft 126, Fig. 8, the wheel having two peripheral projections 127 upon opposite sides adapted 70 to engage the finger 124 of the armature. The shaft 126 is operated by a spring motor, now to be described.

Upon the farther end of the main shaft 41 is a sprocket wheel 130, and sprocket 75 chain 131 carries power from wheel 130 to another sprocket 132 on a shaft 133 ar- ranged parallel to the main shaft. Paral- 80 lel to and at the side of shaft 133 is a travel- ing sleeve 134, carrying a gear 135 meshing with a gear 136 mounted on a sleeve 144, see Fig. 13 and having a clutch connection to shaft 133 as described later on. The sleeve 134 is threaded interiorly and such thread 85 engages the threaded end of a short shaft 137 arranged in alinement with the sleeve, and supported in suitable bearings, and shaft 137 carries a gear 138 meshing with gear 139 on a shaft 140, see Fig. 7 at the side of and par- 90 allel with shaft 137. Shaft 140 also carries a gear 141 meshing with gear 142 on shaft 126. Gear 138 also meshes with a gear 143 on shaft 133.

The sleeve 134 moves longitudinally when rotated by reason of its screw connection 95 with shaft 137, and by these movements it controls the clutch between shaft 133 and the gear 136. The details of the construction by which these results are obtained are best shown at Figs. 6, 7, 12, 13 and 14, and are as 100 follows: On the outer end of the sleeve 134 is a disk 145, the periphery of which extends into the open space between the limbs of a fork 146 formed on the end of a lever 147 pivoted so as to swing horizontally on a 105 standard 148. An arm 149 extends laterally from the stem of a yoke 150 and has a bearing for a rod 153. Between the arms of the yoke 150 is hung a ring 151 encircling the sleeve 144 of gear 136 and which has its in- 110 terior surface beveled, as seen in Fig. 13, to slide onto correspondingly beveled ends of pivoted dogs 161, as hereinafter described. The yoke 150 is pivoted at its lower end at 152, so that it may oscillate and move the 115 ring 151. The rod 153 is rigidly secured to an upstanding member 147^a, the latter being swivelly mounted on the lever 147, said mem- 120 ber 147^a extending at right angles to the plane of the lever 147, as shown more clearly 125 in Fig. 13. The rod 153 is slidably mounted in stationary brackets 154 and mounted on said rod 153 is a coil spring 156, the latter being held under compression by means of the arm 149 on the yoke 150 and a nut 156^a 130 mounted on the rod 153. Also mounted on the rod 153 and on the opposite side of the arm 149 to that on which the spring 156 is located, is a second nut 155, the func- 135 tion of which is hereinafter described. 130

- The yoke 150 is normally held in the position shown in Fig. 13 against the action of the tension spring 163, by means of a latch 157 pivoted at 158 to a stationary arm 159 of the frame, said latch 157 being normally controlled by a spring 157^a, and, as will be understood, the latch 157 is provided with a notch at its inner end engaging a part 250 of the yoke 150.
- 10 The operation of the structure above described is as follows: When the sleeve 134 moves toward the center of the machine, the arm 147^a on the lever 147 will move outwardly or to the right, as viewed in Fig. 13, and in so doing, the rod 153 will also be moved in the same direction, thereby compressing the spring 156 between the arm 149 and the nut 156^a on the rod 153. As the movement of the member 147^a continues, it 20 will engage a projection or cam 160 on the under side of the latch 157 and operate the latter against the spring 157^a, whereupon the latch 157 will release the ring 151 and the yoke 150 will be suddenly moved under 25 the impulse of the spring 163, thereupon throwing the ring 151 suddenly against the beveled ends of the dogs 161, and disengaging the latter from the ratchet 162. On an outward movement of the sleeve 134, the 30 lever 147 will be moved in the reverse direction, thereby pushing the rod 153 inwardly until the nut 155 thereon engages the arm 149, whereupon the yoke 150 will be returned to its normal position against the action 35 of the spring 163 until the latch 157 finally engages the ring 151, whereupon all the parts become locked in their normal position, such as shown in Fig. 13.
- The clutch described is inserted at the 40 point described in order that all the actuations received by the sprocket wheel 132 may not be communicated to gear 136 and cause the winding up of spring 136^c attached to gear 136 when such winding is not needed, 45 and the clutch is thrown into and out of action by the screw threaded sleeve 134, as already stated. It will be understood that gear 136 and its sleeve 144 and spring cylinder 136^c are loose upon shaft 50 133 so that they do not turn with said shaft when it is actuated to wind up the spring except when the clutch is closed, and the tension put upon the spring is retained by the engagement of the pawl 136^a with the ratchet 55 136^e formed on the cylinder, Fig. 18. This however does not prevent the shaft from being turned by the spring, and such movements occur whenever the locking disks 164 and 165 on shaft 137 are released by their 60 bolts as now to be described. Shaft 137 carries a gear 138 meshing with gear 143 on shaft 133, and said disks are somewhat similar to the disks 64 and 65 on the main power shaft, being each provided upon their 65 peripheries at diametrically opposite points with an abrupt shoulder or stop 166 and also having in proximity to the peripheries of the disks two sliding lock bolts 167, 167, one adapted to engage the shoulder upon one of the disks and the other to engage that upon 70 the other disk. The disks are also fast on shaft 137 and keyed thereto so that the shoulder upon one is located midway circumferentially of that upon the other, thereby adapting them to arrest shaft 137 at each 75 half turn when they are themselves arrested by the bolts 167 as seen at Fig. 11, a double eccentric 169 being mounted upon the shaft 140 within the openings in the bolts and thus adapted to position the bolts in operative positions relative to the disks in alternate order and likewise retracts them alternately.
- 80 The sleeve 134 moves one way when the gear 135 is turned by gear 136, and in the reverse direction when shaft 137 is actuated by gear 138, but excessive winding is prevented by the opening of the clutch as above described which prevents the winding up 85 actuation of gear 136, this being due to the 90 action of the sleeve upon the clutch.
- The gear 139 also contains a power storing spring, see dotted lines in Fig. 11, similar to spring 72 which is wound up when said gear is turned by gear 137. This 95 spring, shown in Fig. 11, turns shafts 140 and 126 whenever the wheel 125 is released by the armature 122. The wheel 125 is provided with means whereby its engagements with the armature may be softened so as to 100 avoid any injurious shock to the electrical devices, these means being desirably constructed as follows: On the outer end of shaft 91 is a crank 171, see Fig. 5, and this crank is joined to a pitman 172, the lower 105 end of which is joined to an arm 173 upon a rock shaft 174 extending transversely of the machine, and carrying a segment gear 175 meshing with another segment gear 176 upon another transverse shaft 177 at the 110 side of and parallel with shaft 174. These shafts 174 and 177 are connected to and operate the signals as described below, but one of them has also an arm 178, see Fig. 16, connected by a rod 179 to a sliding bar 115 180 having an enlargement or cam 181 on its under surface. The bar 180 moves horizontally over a beveled projection 182 on the side of a vertically movable stop 183, and when the cam passes the projection, the 120 stop is depressed against a supporting spring 184 with which it is provided. The stop is normally in position to intercept the wheel 125 by its engagement as shown at Fig. 16 with lugs 185 on the side face of 125 the wheel. There are two lugs 185 at diametrically opposite points, and they are so located on the wheel relative to the projections 127 by which the armature locks it, that the stop 183 will be able to deprive 130

the wheel of most of the momentum received from the motor spring of gear 139 before the next projection 127 engages the armature, the wheel moving but a short distance 5 after encountering the stop 183, before it engages the armature. The stop 183 acts to detain the wheel only momentarily, as the cam 181 which immediately comes into action, forces it downward sufficiently to free 10 the wheel and allow it to move on and into engagement with the armature.

Shafts 174 and 177 carry cranks 186 and 187 and one of these, 186, is pivotally attached to a sliding bar 188 and the crank 15 187 is pivotally attached to a sliding bar 189 parallel to and at the side of bar 188, but with an open space between. The shafts are always rocked in opposite directions, and consequently they move the bars 188 and 20 189, which I call the power bars, always in opposite directions. Resting upon bar 188 is a bar 190 and upon bar 189 is a bar 191. These bars 190 and 191 I call the signal bars because they are connected to and operate 25 the signals. Both are parallel with the bars supporting them, and adapted to be locked to them by spring actuated catches 192 (see Fig. 23) located in longitudinal recesses 193 formed in the upper faces of 30 the power bars and adapted to enter recesses 194 formed in the lower faces of the bars 190 and 191. The catches are adapted to spring up into engagement with the bars 190 and 191 whenever in the sliding movements 35 of the bars the catches come into register with the recesses 194 and thus lock bars 190 and 191 to their respective power bars, so that they will move with the power bars when the latter are actuated by the 40 cranks 186 and 187. To release this lock upon the signal bars, the catches are provided with laterally extending lips 195, see Fig. 27, which are engaged by rising and falling plates 196 and 197 located close up 45 against the inner side faces of the two pairs of bars. The plates are both connected by posts 198 to arms 199 projecting in opposite directions from a rock shaft 200 located centrally over the open space between 50 the two pairs of bars. The plates are L shaped in cross section, and they are adapted when lowered to press upon the lips 195 of any catches which may be in action at the time and by depressing the catches cause the 55 release by them of the bar which they may be locking. The plates are guided in their rising and falling movements by recesses 201 in the end pieces 202.

The movements of the shaft 200 are effected in the following manner. Referring 60 more particularly to Figs. 7 and 10 and assuming that the parts are in the position there shown, the energization of the magnet 121 will attract the armature 122 thereby 65 releasing the disk 125 and permitting it to

rotate a half revolution. This rotation takes place due to the fact that the shaft on which the disk or wheel 125 is mounted, upon being released, is operated through the gears 142 and 141 by the stored-up energy of the 70 spring within the gear 139, which spring rotates the shaft 140 on which the gear 141 is mounted. The rotation of the shaft 140 reverses the position of the locking bolts 167 in the manner previously described, thus releasing the locking disks 164 and 165 and permitting them to rotate a half revolution. These disks are rotated a half revolution owing to the stored-up energy in the spring within the case 136 through the intermediary of the gears 143 and 138. The shaft 137, upon which the locking disks and gear 138 are mounted, is thus rotated through an arc of 180° and movement is imparted to the pitman 204 from a crank 203 which is 80 pivotally connected to a lever arm 205 rigidly attached to the shaft 200. In a similar manner, when the magnet 120 is energized the armature 122 will be pulled thereagainst and the disk 125 permitted a half revolution 85 as before described and the shaft 200 rocked in the opposite direction. As will be understood, if the parts are in the position shown in Fig. 7 and the magnet 120 is energized, no movement of the selecting mechanism is necessary, since the parts are all in the proper position. The shaft 200 also carries oppositely extending arms 206, each adapted to enter a notch 206^a provided in the proximate side of each of the signal bars 90 and thus to lock the signal bars against moving with the power bars. These arms act alternately, one being raised so as to release one of the bars at the same instant the other is lowered and locks the other bar. 95

Below the power bars is a plate 207 also adapted to slide and acting as hereinafter described in conjunction with the pipe line 208 which is supported alongside of the power bars in the usual manner between 100 pairs of grooved rollers 209. The plate is provided upon its upper face with four spring actuated catches 210 similar to the catches 192, but instead of having laterally extending lips similar to the lips 195 the 105 catches are located so that the rising and falling plates 196 and 197 bear directly upon them. Two of the catches are under each of the power bars, and these, while they have different pivots, have a single integral lifting spring common to both of them, each end of the spring actuating one of the pair, as will be understood from Fig. 26. The catches enter into and engage recesses 211, in the bottom surfaces of the power bars, and cause the movement of the pipe line with that one of the power bars which is thus engaged, only one being engaged at any one time. The catches are withdrawn by the plates 196 and 197 as will be under- 110 115 120 125 130

stood. I surround the signal and power bars and the plate 207 by a box 212 having vertical side walls and a bottom and by means thereof keep all those parts in their proper relative positions and the side walls are provided with longitudinal ribs which fit into grooves in the side of the bars and plate and guide them when sliding. The box also supports the bearings of the shaft 200.

As a safety means to come into operation whenever the main power cylinder becomes exhausted so that there is not enough power left in it to operate the signals properly, I add to the machine the following mechanism best shown in Figs. 4 and 7. At 213 is a bar supported at one end on the frame of the machine with freedom to move longitudinally, and pivoted at its other end to the end of a lever 214, pivoted at 215 and joined at its farther end to a sliding piece 216. The piece 216 is united pivotally to a bar 217 and passes through and slides in an opening in the turned up edge of a stationary plate 218, and a spring encircles the piece 216 between its union to the bar 217 and the plate 218 so that it will be compressed when the bar is moved toward the plate. Beyond the plate the bar is united to one end of a lever 219 pivoted at 220, and from the other end of said lever extends another rod 221, carrying an arm 222 adapted to engage the collar 98 on the sleeve 93, Fig. 4. The sleeve is moved longitudinally in operating the signals, and when carried toward the arm 222, so that contact occurs between the collar and the arm, the rod 221 will be carried with the collar. This movement results in swinging lever 219 and the actuation, through the intervening mechanism, of the bar 213. The bar 213 carries near its end a projection 223 having an inclined top, Fig. 31, and passing under the foot 224 of a lever 224^a, pivoted at 225 and carrying at its upper end a set screw 226 bearing on the foot 227 of the armature 87 of the magnet 88. A spring 228 presses the lever 224 upward from the magnet foot, so that when the cam projection 223 passes under the lever, it compels the lever to overcome the spring and to depress the foot of the armature, thereby throwing the armature toward the wheel 83 and into locking engagement with lug 85. While this engagement continues, the signal is locked at danger and the motor can do no work as its springs cannot be released for operation, but the wheel will be released and the signal cleared so that those operations can be renewed when the next train moves past, as any such train will cause the winding of the motor springs.

The sliding of plate 86 is caused by the shaft 174 through the medium of a crank 229 attached to the shaft, a pitman 230 con-

necting the crank to the lower end of a swinging lever 231 having its upper end freely jointed to the slide and pivoted at 232.

With each of the magnets, I use a swinging plate adapted to prevent contact between the magnets and their respective armatures except when the magnets are energized. These prevention plates are pivoted at one end and provided with lifting springs at 75 the other end. In the case of magnet 88, Fig. 28, the plate is shown at 233, is pivoted at one end on post 234 and supported at its other by spring 235 surrounding an upright 236, and is provided with a horizontal 80 projection 237 adapted to prevent contact by the armature with the magnet. In the case of magnets 120 and 121, the prevention plates are shown at 238 and 239, and are supported at one end on pivot 240, and at 85 their other ends rest upon springs 241 and 242 surrounding uprights 243 and 244, and are provided with projections 245 and 246 to prevent the contact. All the prevention plates are drawn down by the magnets when 90 the latter are energized sufficiently to permit the necessary contact, and are forced up into acting position again as soon as the electric current ceases.

I have illustrated at Fig. 35 a suitable 95 method of wiring to be employed in connecting magnets 88, 120 and 121 with the railroad track. In illustrating this wiring I call attention to the fact that the energizing of magnet 88 is dependent upon the first 100 energizing of one or the other of magnets 120 or 121, provided the selector mechanism is not in position to cause the main motor to operate the signal and track instruments in accordance with the direction in which 105 the train is approaching. If the selector mechanism is in the proper position then the current flows direct to the signal magnet without operating the selector. I also place in the wire two reversely operable relays 110 250 and 251, the construction of which is shown in Patent #695649, granted to me March 18, 1902 and an ordinary track relay in which all the contacts are normally closed 115 is shown at 252. I also show the track divided into sections *a*, *b*, *c*, *d* and *e*, by insulators 253, and each of the sections has its own individual track battery 254, maintaining a closed circuit in it.

The relays 250 and 251 are each so constructed that there is normally a break between the points O and B thereof when both magnets of the relay are energized and all contacts are normally closed between the points 3—3 thereof. When, however, either 125 of the magnets of the relay is deenergized, a break will be formed between the points 3—3, and when both magnets of the relay are deenergized in the proper sequence, the circuit will be closed between the points O 130

and B thereof, this latter condition being shown in Fig. 36, where the magnets of the relay have been deenergized in the proper sequence; that is, by deenergizing the magnet X first and the magnet Y second. Should this relay, however, have been deenergized in a different manner, that is, by first deenergizing the magnet Y and subsequently the magnet X, then not only would the circuits be broken between the points 3—3, but the contacts between the points O—B would also be held open. This operation is fully described in my said Patent No. 695,649.

15 The operation of this part of the apparatus is as follows:

When a train is moving westward over the track, it first enters the track section *a*, thereby causing the deenergization of the magnet 20 X connected to the rails by the wires *a*¹ and *a*² and normally energized by track battery 254, and allowing the armature *x* to fall back, as shown in Fig. 36, in the reversely operable relay 250, and breaking the circuit 25 between the points 3—3 thereof and as the train proceeds and reaches track section *b*, magnet Y, which is connected to the rails by wires *b*¹ and *b*², will be deenergized, thereby allowing armature *y* to fall and 30 causing another break between the points 3—3, but closing the circuit between the points O—B of the relay, as shown in Fig. 36. When the circuit is closed between the points O—B of relay 250, a clearing circuit 35 for the signal is formed, which, starting from battery 264 goes by wire 274 through O—B of relay 250, wire *b*³ through the points 3—3 (normally closed) of relay 251, through wire *b*³ to corresponding points 40 3—3 of relays in the next block, back through wire *b*³ to wire *b*⁴ of the circuit breaker, designated generally by the reference 257, see Fig. 35. This circuit breaker comprises four sets of contacts 258, 259, 260 45 and 261, the contacts 258 and 259 being opened or closed simultaneously, the contacts 260 and 261 being also closed and opened simultaneously, but so arranged that when the contacts 258 and 259 are either closed 50 or open, the other pair of contacts 260 and 261 will be in the reverse condition. From wire *b*⁴, the current will pass through either the contacts 259 or 261, depending upon which of them are closed. If contacts 259 55 are closed, then the current will pass through wire *b*⁵ and wire *b*¹⁴ directly to magnet 88, thereby energizing the latter and returning by wire *b*⁶ through the closed contacts in the track relay 252, back to the 60 opposite side of the battery 264. If the contacts 259 are closed when a westbound train is passing over the track, this shows that the selector mechanism is in the proper position, and hence as soon as the magnet 88 be-

comes energized, the signals and train stops 65 or track instruments will be shifted. Should, however, the contacts 259 be open, and the contacts 261 closed, when a westbound train passes over the track, this shows that the selector mechanism must be 70 shifted so that the proper westbound signals and track instruments can be operated, and the current will then flow from wire *b*⁴ through the contacts 261, through wire *b*⁷ to selector magnet 120 (previously described 75 in connection with the selector mechanism and shown in Fig. 33), thence back by wire *b*⁶ through track relay 252 to the opposite side of battery 264. Upon the magnet 120 becoming energized, the selector mechanism 80 will be operated, as previously described, and at the same time the condition of the contacts 258, 259, 260 and 261 will be reversed on account of the slide 290 being moved, see Fig. 10, whereupon contacts 259 85 will be closed and current will then flow directly through wire *b*⁵ and wire *b*¹⁴ to the magnet 88 and back to the battery 264, as previously described, and upon the magnet 88 becoming energized, the shifting mechanism 90 will be operated, as before described.

For an east bound train, the operation is as follows: As the train passes over track sections *e* and *d*, the magnets in the relay 251 will be deenergized, thereby breaking 95 the contacts between the points 3—3 thereof, and closing the circuit between the points O—B. A clearing circuit is then formed which, starting from battery 264 passes through wire 274, through B—O of 251, then 100 by wire *b*⁸ through 3—3 of 250, wire *b*⁸ to corresponding points 3—3 of relays in the block to the right of that shown in Fig. 35 and back by wire *b*⁸, wire, *b*⁹, wire *b*¹⁰ to the contacts 258 and 260. If contacts 260 are 105 closed, then the circuit is completed through the same directly to magnet 88 through wire *b*⁵¹ and *b*¹⁴, and back through wire *b*⁶, front points of track relay 252, back to the opposite side of battery 264. If the contacts 260 110 are closed, this shows that the selector mechanism is in proper position for the shifting mechanism to operate the eastbound signals and track instruments. If, however, the contacts 260 are open and the contacts 115 258 are closed, the circuit will be completed through the latter through wire *b*¹⁶ and through the selector magnet 121 (previously described in connection with the selector mechanism and shown in Fig. 33), thence 120 back by wire *b*⁶, through front points of relay 252 to the opposite side of battery 264. Upon the magnet 121 becoming energized, the selector mechanism is operated, thereby 125 causing a reversal of the conditions of the contacts 258, 259, 260 and 261, and closing contacts 260, whereupon the circuit is completed directly to the magnet 88, as before

described. Of course it will be understood that whenever either of the selector magnets is energized as above stated, the signals are cleared so that the train will be at liberty 5 to proceed, but when the train arrives at track section *c* from either direction, it short circuits the battery of that section, causing relay 252 to be deenergized and breaks the circuit of battery 264, and the machine then 10 moves the signals to danger.

I contemplate using with the power machine and the selecting mechanism above set forth, the ordinary train stops whereby to automatically set the brakes of a locomotive 15 passing over the block section in disregard of the signals, and indeed have provided in said selecting apparatus means for shifting the pipe line 208 which is used with such train stops by connecting the pipe line 208 with 20 the plate 207 by means of the arm 310, which is clearly shown in Figs. 2, 6 and 7, the plate 207 having already been described in an early part of this specification. The train stops are indicated at 300 and 301 in 25 the apparatus as illustrated in Fig. 35. I have not illustrated them in detail as their construction is well known and may be greatly varied. A suitable construction for them is disclosed in my Patent No. 776,146 30 of November 29, 1904. I also give in the same figure a suitable location 302 of the signal station of the apparatus. The instruments 300 and 301 are always in opposed positions, and are mechanically connected by 35 means adapted to reverse the positions of both simultaneously whenever the locomotive passes either one of them. The means by which this is done includes the pipe line 208 and the arm 310 connecting the same 40 with the plate 207. In this way the spring motor operates the train stops at the proper time and in accordance with the movements of the signals. The train stop which has been passed by the locomotive must of course 45 be in the clear or inoperative position, and the other instrument to be passed later will be at danger and the movement from the pipe line reverses these positions. If the first train stop in the order of approach is in 50 the operative position before the train reaches it, the selector mechanism will reverse the positions of the locking dogs between the power bars and the signal bars and bar 207, so that the train stops will be reversed at the same time that the visual signals are cleared, and as the visual signals return to danger the positions of the train stops will be again reversed which operation occurs between the time when the train has 55 passed the first train stop and before it reaches the second train stop. The manner in which the locking dogs are reversed has been already described in connection with the operation of the rock shaft 200 when the 60

selector magnet 121 is energized and in connection with the operation of the track circuits, relays 250 and 251 and contacts 258, 259, 260 and 261, etc.

The operation of the mechanism described is as follows in detail: Each truck of a train 5 to passing over rail 47 presses bar 48 downward and imparts a reciprocating movement to lever 45. Rack 49 is thus moved up and down and rotates 54 and 55 back and forth on 41. In the forward movement of 55 70 pawls 57 Fig. 19 engage teeth on 56 and carry cylinder 40 with 56. Pawls 59 engage these teeth in the opposite direction and prevent 40 from following 55 in its backward movement and springs 44—Figs. 17 and 21— 75 80 are thus wound. As 40 is rotated, it, by means of gears 96 and 97, rotates sleeve 93 causing it to be screwed onto shaft 91. As this forward movement continues, collar 98 contacts with the upwardly extended finger 85 of 99 and rocks it on pivot 100, compresses spring 101, carries 110 with it until hooked end contacts with and removes pawl 107 from the path of 102, allowing spring 101 to quickly expand and shoot pawl 105 into complete engagement with teeth 106 on the side of 49 thus holding 49 in the upward position and preventing further winding of the springs 44.

The machine is now wound, and in describing the operation of expending its energy I will assume the selector to be in such position as requires it to be shifted, in which case the selector is the first portion of the apparatus to be operated. Magnet 121 is energized, plate 239, Figs. 33 and 34, is attracted downward and removes 246 from the path of armature 122 which is drawn toward 121. This removes 124 from the path of lug 127 on one side of wheel 125 and into the path of 100 its mate on the other side of 125, Figs. 7 and 8. The spring in gear 139, which is the same construction as that shown at Fig. 22, rotates shaft 140 and by means of gears 141, 142 rotates shaft 126 and wheel 125, which is 105 fast thereto. One of the lock bolts 167 is thus withdrawn and the other inserted (see Fig. 11). The spring contained in 136, shown in detail, Fig. 18, rotates shaft 133 and by means of gears 143 and 138 rotates 110 shaft 137 one half revolution until stopped by one of the lock bolts 167; the movement of shaft 137 by means of gear 138 rewinding the spring in 139 which was exhausted by rotating 140. It also rocks shaft 200 by 115 means of crank 203 and pitman 204, and by the link shown, extending in the opposite direction from 203 operates circuit breakers 258—259—260—261 (see Fig. 35), and being screw threaded into 134, forces 134 outward 120 to the extent of one half revolution of the thread. The rocking of shaft 200 raises plate 196 and lowers 197 thereby pressing

dogs 192 carried by bar 188 out of connection with signal bar 190 and allowing dogs 194 carried by bar 189 to engage bar 191, and also allows dogs 210 carried by 207 to engage bar 189, when recess 211 is over them and 5 also inserts arm 206 into notch 206^a in 190 so that 190 cannot be moved while the arm is in this position—(see Figs. 23, 24, 25, 26 and 27). The selector has now completed its 10 movements, circuit breakers 258 and 259 have been opened and 260, 261 closed so that current from wire b⁹ flows through 260 direct to magnet 88 (see Fig. 35). Magnet 88 being energized, plate 233 is attracted down- 15 ward, 237 removed from the path of 87, allowing 87 to respond to the attraction of 88 which removes it from the path of one of the lugs 85 on one side of the wheel 83 and into the path of its mate on the opposite side. 20 The spring in gear 81, the same as that shown in Fig. 22, rotates shaft 80 one half revolution until stopped by lug 84 on 83 coming in contact with 86; this withdraws one of the swinging arms 76 from the path 25 of its lug 75, on the periphery of wheel 74, and inserts the other so that shaft 70 is rotated one-half revolution by means of the spring in gear 71. This moves one of the lock bolts 69 out of the path of lug 66 on 30 disk 64 and its mate into the path of 66 on 65. As these disks are fast to shaft 41, the changing of lock bolts 67, as above described, allows 41 to be rotated one quarter revolution by the force of springs 44 in 40 (Figs. 35 19—20 and 21).

The movement of the shaft 41 through the medium of gears 73 and 90 rotates shaft 91 one half revolution and this by means of crank 171, pitman 172, arm 173 and segment gears 175, 176 transmits a reciprocal motion to rock-shafts 174 and 177, which are, by means of arms 186, 187, linked to power bars 188 and 189 respectively of the selector, and by them move the signals and 45 pipe line 208 in accordance with the position of the selector as hereinbefore described, and also slides 93 backward by means of its threaded portion. The movement of 174, by means of crank 229, pitman 230 and lever 50 231 slides 86 back and forth into and out of the path of lugs 84 on 83, so that 86 is always in position to stop 83 slightly before its lug 85 comes in contact with armature 87, thereby preventing shock to 87. The 55 movement of shaft 177 by means of crank 178, pitman 179 and bar 180, removes lock bolt 183 from the path of lugs 185 on 125 as follows: Cam 181 on the lower side of 180 as it slides over 182 on 183, forces 183 down- 60 ward against the pressure of spring 184 allowing 185 to pass over the top of 183 as shown at Fig. 16, 183 stops 125 slightly before it strikes armature 122, preventing shock to 122. As gears 71 and 81 are meshed with 65 73 the movement of shaft 41 rewinds the

springs in them which were exhausted in turning their shafts 70 and 80. It also by means of sprocket wheels 130 and 132 and chain 131 rewinds the selector springs in 136^c. 70

As has been stated, two track instruments are provided at each signal station, one at an appreciable distance in each direction from it. These track instruments are always in opposed relation, one being up and 75 the other down and the two sets of signaling means each of which may consist in the present instance of a single arm and attendant parts are normally at danger. A train passing the signal station must clear 80 these track instruments successively, and a positive movement which reverses their positions is therefore required. If the train approach from the side of the instrument, which is lowered or in inoperative position, 85 clearing of the signal accomplishes no movement of the track instruments and this to permit the train to pass the first track instruments in its direction of travel. When the signal goes to danger the track instruments are reversed in their opposed relation 90 to let the train by the second track instrument. When, however, a train comes from the opposite direction the track instrument must be reversed in their relations to permit the train to pass the first instrument when 95 the signal clears, and reverses in their changed relation again when the signal goes to danger to permit the train to pass the second instrument. This operation is governed 100 by the arrangement of the power bars with respect to the track instrument bar 207 and arrangement of the latches 210 and recesses 211. The dogs on the plates 207 for the two power bars are mounted side by side. 105 When a train is clearing a signal and operating a track instrument previously arranged in inoperative position, the dogs 210 left free upon the clearing of the signal are not in position to engage in the recesses 211 110 until after an operation of the power bars, such operation bringing appropriate recesses 211 over them in position to permit return movement of the power bars to set the signal at danger to reverse the position of the track 115 instruments. The train approaching from the other direction, *i. e.* approaching a train stop previously in operative position, the dogs 210, which are free, are opposite their companion recess 211 and reversal of 120 the train stops occurs when the signal clears. In other words, the locks 196 and 197 prevent operation of the track instruments when a signal clears if such track instruments are already appropriately arranged. 125

Fig. 39 is provided to show in more particularity the position of the terminals 258, 259, 260 and 261 on the slide 290, and in the easing 291 and the arrangement of the various wires connected directly to these parts. 130

This figure should be read in connection with Fig. 35, it being understood that the slide 290 is caused to move from one extreme position to the opposite extreme position 5 under the influence of the link 293 each time the disk 125 is released to permit actuation from the shaft 140 (see Fig. 7). When in the extreme left-hand position viewing Fig. 39, terminals 258 and 259 are closed, and 10 when in the extreme right-hand position viewing this figure terminals 260 and 261 are closed. Energization of magnet 120 through terminals 261 causes a shift from extreme right-hand to extreme left-hand position, 15 and energization of magnet 121 through terminals 258 causes a return movement as has already been fully described in connection with the wiring shown in Fig. 35.

I claim:—

20 1. The combination in a block signal system of a spring motor wound up by passing trains, said motor including a cylinder having a plurality of springs therewithin, a magnet, the energization of which is controlled by the trains, and connecting mechanism between the magnet and said motor, whereby the magnet controls the expenditure of power by the motor, said connecting mechanism including means for temporarily 25 interrupting movements of its parts to thereby prevent shock, substantially as specified.

2. The combination in a block signal system, with a spring motor, of opposing signals, actuating bars connected to the signals 35 for setting the same, selecting mechanism controlling said actuating bars in accordance with the direction of the approaching train and embracing a rock shaft adapted to be rocked in opposite directions and by the direction in which it is rocked to determine 40 the action of the selecting devices, and separate magnets, one for each direction, the energization of which is controlled by the trains, and acting to determine the action of said 45 rock shaft.

3. The combination in a block signal system with a spring motor, of opposing signals, actuating bars connected to the signals for setting the same, selecting mechanism 50 controlling said actuating bars in accordance with the direction of the approaching train and embracing sliding bars selectively mechanically united to said first named bars, a rock shaft governing the operation of said 55 sliding bars, and separate magnets, one for each direction, the energization of which is controlled by the trains and acting to determine the action of said rock shaft.

4. The combination in a block signal system 60 with a spring motor, of opposing signals, actuating bars connected to the signals for setting same, selecting mechanism controlling said actuating bars in accordance with the direction of the approaching train 65 and embracing power bars, means for lock-

ing the actuating bars to the power bars, a rock shaft for releasing said locking means and two separate magnets, the energization of which is controlled by the trains, one for each direction, and adapted to cause the operation of said rock shaft in accordance with the direction of the train. 70

5. In a block signal system, in combination: signals; power mechanism for selectively operating the signals and including 75 selector magnets provided with a common armature, a wheel 125 engaged by said armature, spring actuating means for operating said wheel, and means for depriving the wheel of momentum just before it engages 80 the armature, substantially as specified.

6. In a block signal system, in combination: signals; devices for operating said signals; train stops operated in connection with said signals, a pair of stops being always in 85 opposed positions; a power machine; a magnet controlling the expenditure of the power from said machine; and signal selecting mechanism, the latter including selector magnets controlling the operation of the 90 mechanism in accordance with the direction of the moving train, substantially as specified.

7. In a block signal system, in combination: signals provided with operating devices connected thereto; a pair of train stops operated in conjunction with said signals, said train stops being so arranged that one will always be at danger while the other is at safety; selecting mechanism operating the 100 train stops; a power machine for actuating said selecting mechanism; and means controlling said selecting mechanism in accordance with the direction of the passing trains, 105 substantially as specified.

8. In a block signal system, in combination: signals provided with operating devices connected thereto; two train stops having safety and danger positions and always arranged in opposed relation and having 110 mechanism for shifting and reversing the positions of the same; a power machine mechanically connected to and operating said reversing and shifting mechanism; means for controlling the expenditure of power by 115 said power machine; and means whereby the actuations of said shifting and reversing mechanisms received from the power machine will be controlled in accordance with the direction of passing trains, substantially 120 as specified.

9. In a block signal system, in combination: signals; a pair of train stops always arranged in opposed relation; mechanism for shifting and reversing the positions of said 125 train stops; a power signal operating machine mechanically connected to and operating said mechanism; and means controlling the actuation of said shifting and reversing mechanism by said power machine in accord- 130

- ance with the direction of passing trains, substantially as specified.
10. In a block signal system, in combination: signals; a pair of train stops operating in conjunction with said signals, said train stops having safety and danger positions and always arranged in opposed relation; mechanism for shifting and reversing the positions of said train stops; a power signal operating machine mechanically connected to and operating said shifting and reversing mechanism; and means controlling the actuations of the signals and the reversing mechanism in accordance with the direction of passing trains, substantially as specified.
11. In a block signal system, in combination: signal devices; a pair of train stops operated in conjunction with said signal devices, said train stops being normally in opposed relation relatively to each other; a spring motor; and means operated by said motor for shifting and reversing said train stops in accordance with the direction of movement of a train, substantially as specified.
12. In a railway control system of the character described, in combination: a motor; signals for each direction of movement of the trains; longitudinally reciprocable power bars, one for the signals in each direction, operated by said motor; and selectively controlled devices operated by the train intermediate said bars and the signals for operatively connecting a power bar with its signal and in accordance with the direction of movement of the train, substantially as specified.
13. In a railway control system of the character described, in combination: a motor; visual signals for trains going in both directions; train stops; power bars operated by the motor; and means for simultaneously selectively connecting a power bar with the train stops and with its corresponding signal to thereby operate the signals and train stops, substantially as specified.
14. In a railway control system of the character described, in combination: a motor; signal devices for trains going in both directions and having signal bars connected therewith; two longitudinally reciprocable power bars operated by said motor; members adapted to lock the power bars and signal bars together whereby movement of a power bar causes movement of a signal bar; and means, selectively operated according to the direction of movement of a train, for rendering inoperative the connection between one of the power bars and its corresponding signal bar, substantially as specified.
15. In a railway control system of the character described, in combination: a motor; signal devices having signal bars connected therewith; a pair of power bars op-
- positely and simultaneously operable by said motor; locking members adapted to lock the power bars and the signal bars together whereby movement of a power bar causes movement of a signal bar; and selectively operated means for positioning the locking members to lock a power bar with a signal bar in accordance with the direction of movement of a train, said means including track circuits and a magnet, the energization of which is governed by said track circuits, substantially as specified.
16. In a railway control system of the character described, in combination: a motor; a pair of train stops mechanically connected and simultaneously operable, one from operative to inoperative position and the other from inoperative to operative position and vice versa; power members connected to the motor and operated thereby; and selectively operated means for connecting the power members to the train stops for reversing the positions of the latter, substantially as specified.
17. In a railway control system of the character described, in combination: a motor; signal devices having signal bars connected therewith; power bars operable by said motor; and selectively operated means for connecting a power bar with a signal bar to thereby transmit movement from the one to the other, said means including a pair of track circuit governed magnets, an armature operated by said magnets and a shaft normally held stationary but released when the armature is moved, substantially as specified.
18. In a railway control system of the character described, in combination: a motor; signal devices for trains in both directions and having signal bars connected therewith; power bars corresponding to the signals for each direction; locking members for locking a power bar with its corresponding signal bar; and means, selectively operated according to the direction of movement of a train, governing the locking of a power bar with its signal bar, said means including two magnets, one for each direction of movement of the train, a common armature, and devices intermediate the armature and said locking members for moving said locking members to release positions upon movement of the armature, substantially as specified.
19. In a railway control system of the character described, in combination: a motor; power members operated thereby; signals having signal bars connected therewith; a plurality of pivotally mounted pawls adapted to connect the power members with their corresponding signal bars; and means for moving some of said pawls to an inoperative position, substantially as specified.
20. In a railway control system of the character described, in combination: a mo-

- tor; visual signals for trains in both directions; a pair of train stops simultaneously operable and always in opposite directions; power members operated by said motor; and means, selectively controlled in accordance with the direction of movement of a train, for simultaneously operatively connecting a power bar with its corresponding visual signal and the train stops, substantially as specified.
21. In a railway control system of the character described, in combination: a motor; visual signals; a train stop; power members operated by said motor; and means, selectively operated, for connecting a power member with its corresponding signal and the train stop, said means including a magnet, the energization of which is controlled by track circuits, an armature associated with said magnet and devices for protecting the said magnet from damage through movement of said armature, said devices being moved to inoperative position before the end of movement of said armature, substantially as specified.
22. In a railway control system of the character described, in combination: a motor; visual signals for trains in both directions and having signal bars connected therewith; a pair of power bars longitudinally reciprocable and operated by said motor; a train stop having a bar connected therewith; and means, selectively operated in accordance with the direction of movement of a train, for simultaneously operatively connecting a power bar with its corresponding signal bar and the train stop bar, substantially as specified.
23. In a railway control system of the character described, in combination: a motor; signal devices; power members operable by said motor; means governing the operation of said motor; and means, selectively operated in accordance with the direction of movement of a train, for operatively connecting a power member with its corresponding signal to thereby operate the latter, said means being operable before the motor governing means, substantially as specified.
24. In a railway control system of the character described, in combination: a spring motor; a magnet governing the expenditure of power from said motor; power bars operated by said motor, the power bars being operated simultaneously and oppositely; signal devices; and means, operated in accordance with the direction of movement of a train for operatively connecting a power bar with its corresponding signal, said means being operated prior to the energization of said magnet, whereby the selecting of the signal to be operated is effected prior to the operation of the motor, substantially as specified.
25. In a railway control system of the character described, in combination: a motor; visual signals for trains in both directions and having signal bars; power bars operated by said motor; locking members for locking a power bar with its corresponding signal bar; means for operating said locking members; and means governing the action of said motor, said means operating subsequent to the first named means, substantially as specified.
26. In a railway control system of the character described, in combination: a spring motor; a magnet governing the expenditure of power from said motor; power bars operated simultaneously and in opposite directions by said motor; signals for trains in both directions and having signal bars connected therewith; locking devices intermediate the power bars and signal bars; and selectively governed means, operable prior to the energization of said magnet, for moving said locking members, substantially as specified.
27. In a railway control system of the character described, in combination: a motor; power members operated thereby; signals for trains in both directions and having signal bars connected therewith; a plurality of locking members adapted to connect a power bar with a signal bar; and means for simultaneously placing the locking members associated with one power bar in operative position to connect the power bar with its signal bar and lock the other signal bar against movement, substantially as specified.
28. In a railway control system of the character described, in combination: a motor; power members operated thereby, the latter being operated simultaneously and oppositely; signals having signal bars connected therewith, the signals being arranged for trains in both directions; a plurality of spring-controlled locking members intermediate the signal bars and the power members; and devices for simultaneously moving the locking members associated with one power member to operatively connect it with its signal bar and to lock the other signal bar against movement, substantially as specified.
29. In a railway control system of the character described, in combination: a motor; a pair of power bars operated thereby; signals for each direction of movement of the train and having signal bars connected therewith; locking members interposed between the signal bars and power bars; mechanism controlling the position of said locking members; and means for locking a signal bar in fixed position when another signal bar is operatively connected to its corresponding power bar, substantially as specified.

30. In a railway train control system the combination of a pair of visual signals, a train stop, a motor, and selectively operating connections between said motor and said signals and train stop, said connections having detachable connection with said signals and train stop and bringing a signal under the motive influence of the motor and holding said train stop against movement under 10 predetermined conditions.

31. In a railway train control system the combination of a section of track divided into blocks, sets of signaling means, one for trains going in each direction, a common 15 driving means for said sets of signaling means, shifting mechanism for operating said signaling means, selector mechanisms for each set of signaling means for controlling the operation of the shifting mechanism so 20 that the latter operates the proper signaling means for trains going in a certain direction,

and circuits for controlling the operation of said selector means.

32. In a railway train control system the combination of a section of track divided 25 into blocks, sets of signaling means, one for trains going in each direction, a common driving means for said sets of signaling means, shifting mechanism for operating said signaling means, selector mechanisms 30 for each set of signaling means for controlling the operation of the shifting mechanism so that the latter operates the proper signaling means for trains going in a certain direction, and circuits for controlling the operation of said selector means, said circuits having included therein selector and shifter magnets.
